UNITED STATES PATENT OFFICE.

GEORGE E. DUVAL, OF WAY CROSS, GEORGIA.

STRIPING DEVICE.

No. 894,821.

Specification of Letters Patent.

Patented Aug. 4, 1908.

Application filed August 21, 1906. Serial No. 331,546.

To all whom it may concern:

Be it known that I, GEORGE E. DUVAL, a citizen of the United States, residing at Way Cross, in the county of Ware and State of 5 Georgia, have invented a new and useful Improvement in a Striping Device, of which the following is a specification.

This invention relates to a device especially adapted for laying on stripes or lines of sizing 10 preparatory to forming a letter or design upon a smooth surface of gold leaf.

The device is especially adapted for use of 15 painters employed in lettering and decorating railroad coaches, carriages and large windows.

The invention consists of a reservoir, carrying a felt brush having a comparatively long and narrow edge, and means for holding the said edge parallel to or at a desired angle 20 with a straight edge, thereby regulating the width of surface covered by the brush.

In the drawings forming a part of this specification:—Figure 1 is a perspective view of my invention showing the fountain brush only. Fig. 2 is a section on the line 25 2—2 of Fig. 3. Fig. 3 is a section on the line 3—3 of Fig. 2. Fig. 4 is an inverted bottom view. Fig. 5 is a detail perspective view of the guiding attachment. Fig. 6 is a section through the neck of the fountain taken 30 on the line 6—6 of Fig. 2. Fig. 7 is a perspective view of a cap and retaining means, a portion of the reservoir neck being shown, and the parts being detached. Fig. 8 is a 35 perspective view of the brush.

In constructing my device I employ a reservoir, formed with two telescoping sections A and B. The lower section B has its lower 40 end portion gradually contracted in width by bending in one side, and the upper portion slides over or upon the lower portion of the upper section A. The section A opens downwardly into the section B and carries at its upper end a tubular neck C preferably oval 45 in cross section and at its upper end and upon opposite sides, the neck C is bent over to form beads C'.

A cap D has depending end flaps D' which fit over the beads C' and are locked in position by a ring D² which encircles the neck C and is drawn upwardly over the end flaps D', clamping them to the bottle neck.

A threaded rod E extends into the neck being supported from the cap D and within the 55 neck C works a plate E' through which the

threaded rod E passes, and at its outer upper end the rod is provided with a knurled head E². In the section B is arranged a brush F preferably formed of a piece of felt shaped to fit the interior of the section B and projecting slightly from its lower contracted end. A band G is fitted upon the section B and is provided with an extension along one side as shown at G'. At the opposite end the band G is cut out and the cut out portions rolled over to form sleeves H.

A plate J has similar sleeves J' formed at one end which sleeves are adapted to interlock with the sleeves H and a pintle J² hinges the plate J and the band G together. A set 70 screw J³ works through the extension G' and bears upon the free end of the plate J. It will be obvious that by turning the set screw the angle formed between the band G and the plate J will be varied.

In use the reservoir is filled with a suitable liquid as for example, sizing, white lead or any other material being used, and by turning the head E² the plate E' may be moved upwardly or downwardly, thus either increasing or relieving pressure upon the felt brush F, and increasing or decreasing the flow of the liquid through said brush or pad.

When material as heavy as white lead is used, the brush may be constructed of a pad 85 of more porous material than when employed for use with a sizing for gold leaf.

In use the plate J is guided along the straight edge or through guiding instruments and the width of the line formed by 90 the brush will depend upon the angle which the band G makes with the plate J, which angle can be regulated by the set screw J³, and when the band G and the plate J are exactly parallel with each other, a very light, 95 thin line will be produced.

It will also be obvious that the attachment formed by means of the band G and the plate J can be employed in connection with the section B and brush F without the 100 section A, the brush being dipped into the liquid.

Having thus fully described my invention, what I claim as new and desire to secure by Letters Patent, is:—

1. A combination with a reservoir carrying a brush, of a band carried by said reservoir, a plate hinged to the band, and means for adjusting said plate at various angles of the brush.

105

110

2. A device of the kind described comprising a pad holding means, a pad held therein and projecting therefrom, a hinged plate supported from the pad holding means and adapted to swing at an angle to the longitudinal axis of the pad and a set screw adapted to limit the movement of the hinged plate

in one direction and prevent its swinging into parallel relationship with the axis of the pad.
